SIDE FRAME

Robert B. Cottrell, Chicago, Ill., assignor to
American Steel Foundries, Chicago, Ill., a corporation of New Jersey

Application July 31, 1940, Serial No. 348,627

8 Claims. (Cl. 105—179)

My invention relates to a side frame for a railway car truck and more particularly to a novel arrangement of truss type design particularly applicable to a known type of truck wherein the wheels at opposite sides of the truck are independently secured on short spindles instead of the usual form of a wheel and axle assembly which includes a wheel at each side of the truck and an axle extending therebetween.

An object of my invention is to devise a cast steel side frame of truss type comprising a box-like central portion open at the top to accommodate a known form of connection to a car body bolster member and end portions, each of which is of bifurcated form, comprising a plurality of spaced truss members affording at their extremities means of connection to a wheel supporting spindle or stub axle.

My invention contemplates such a side frame as that above described wherein each half or each truss portion of the bifurcated end of the frame shall comprise top and bottom U-sections merging at their ends to accommodate a journal arrangement as described.

Another object is to design such a side frame with pedestal guide portions at the extremities thereof or, in a modified form, aligned openings suitable for application of a stub axle or spindle.

In a different modification, my invention contemplates an arrangement wherein the top member of the truss comprises a continuous web for each of the bifurcated portions, said web extending continuously from end to end of the frame and, in one modification, encircling the end portions of the frame to merge with the bottom webs.

My invention also includes as an object thereof such a side frame as that described wherein the center well is afforded a bottom wall or spring seat of cylindrical form, said cylindrical portion being struck from the center lying in a plane above the center line joining the axle openings at opposite ends of the frame.

My invention also contemplates such an arrangement as that described wherein the central portion of the frame comprises a box-section beneath the spring seat merging with end portions, each comprising a bifurcated arrangement, each leg of which is of T-section.

A yet different object is to afford a means of tying together the side frame at opposite sides of the truck in a plane defined by the center lines of the axles at opposite ends of the truck.

Describing my invention in greater detail, Figure 1 is a plan view of one modification

thereof, the right half of the figure showing the top plan and the left half the bottom plan.

Figure 2 is a side elevation of the side frame structure shown in Figure 1, half in section, the section being taken in the vertical plane bisecting the structure longitudinally and substantially as indicated by the line 2—2 of Figure 1.

Figure 3 is a sectional view taken in the vertical transverse plane bisecting the frame as indicated by the line 3—3 of Figure 1.

Figure 4 is a plan view of another modification of my novel invention, the right half showing a top plan and the left half a bottom plan thereof.

Figure 5 is a side elevation of the side frame structure shown in Figure 4, half in section, the section being taken in the vertical plane bisecting the frame longitudinally substantially as indicated by the line 5—5 of Figure 4.

Figure 6 is a sectional view taken in the vertical plane bisecting the structure shown in Figures 4 and 5 transversely thereof and as indicated by the line 6—6 of Figure 5.

Figure 7 is a sectional view through one of the bifurcated end portions of the frame approximately at the mid-portion thereof and in the planes indicated by the line 7—7 of Figure 5.

Figure 8 is a sectional view in a vertical plane through one leg of a bifurcated end portion and substantially as indicated by the line 8—8 of Figure 5.

Figure 9 is an enlarged fragmentary sectional view taken substantially in the diagonal plane indicated by the line 9—9 of Figure 4.

Figures 10, 11, 12, and 13 are fragmentary sectional views taken in the various planes as indicated by the lines 10—10, 11—11, 12—12, and 13—13 of Figure 5.

Figure 14 is a plan view of a further modification of my invention, the right half of the figure showing the top plan and the left half thereof the bottom plan.

Figure 15 is a side elevation of the modification shown in Figure 14, half in section, the section being taken substantially in the vertical longitudinal plane indicated by the line 15—15 of Figure 14.

Figure 16 is a sectional view taken substantially in the transverse vertical plane bisecting the frame and as indicated by line 16—16 of Figure 15.

Figure 17 is a sectional view taken diagonally through the end portion of the frame substantially in the plane indicated by the line 17—17 of Figure 15.

Figure 18 is a fragmentary sectional view taken

substantially in the transverse vertical plane indicated by the line 18—18 of Figure 15.

Describing the structure in greater detail and referring first to the modification shown in Figures 1 to 3, the frame is an integral cast structure comprising a central box-like portion 2 integrally formed with bifurcated end portions 3, 3, each of said bifurcated end portions comprising an inboard leg 5 and an outboard leg 7, each with a compression member 9 and a tension member 11 merging adjacent their ends as at 13 to form end portions with pedestal jaws 15, 15 for connection to journal means (not shown). The lower edges of the pedestal walls are afforded aligned openings at 17, 17 for reception of securing means, such as a pin or bolt, for means overlying the spindles or stub axles. The central box-like portion 2 has vertical lateral walls 4, 4 and end walls 6, 6 arranged in rectangular form, said central box-portion 2 comprising also a bottom wall 8 of cylindrical form with the axis of said cylinder extending transversely of the truck, said cylindrical bottom wall 8 being defined along the radius R whose center at 10 lies in a plane above the plane defined by the axes 12, 12 of the axle openings at the opposite ends of the frame. Beneath the bottom wall 8 the central portion comprises a box-section with the spaced substantially horizontal wall 14 extending laterally of the side walls 4, 4 as at 16, 16 to merge with upturned flanges 18, 18 at opposite sides of the frame. Integral webs 20, 20 extend between the flanges 18, 18 and the side walls 4, 4. The box-section is likewise reinforced by spaced webs 22, 22 extending longitudinally of the frame and continuing beyond the end walls 6, 6 to merge as at 24, 24 (Figure 1) with the inner inturned flanges 26, 26 of the tension members 11, 11 of the respective legs of the bifurcated end members. Likewise, the upturned flanges 18, 18 at opposite sides of the central portion are continued into the bifurcated end portions to form the outer flange of each leg thereof so that the flanges 18, 18 are continuous from end to end of the frame as are also the flanges 26, 22, 26. The flanges 26, 26 are widened at their lower ends to merge as at 28, 29 with the end walls 6, 6 of the box-section. So also the webs 21, 21 of the tension members at each end of the frame are continuous with the bottom wall 14, 14 so that said webs may be described as continuous from end to end of the frame and over the journal portions as at 33, 33. Openings are cored in the bottom wall 14 as at 28, 28 and as at 30, 30 in the side walls 4, 4 below the bottom wall 8, the bases of said side walls being extended longitudinally of the frame to merge as at 31, 31 with the web of the tension member. The bottom wall 14 extends as at 32 longitudinally of the frame beyond the central box-portion and is beaded along its edge as at 34. The compression member 9 of each leg is of U-section having a top web 36 with a depending inner flange 38 merging as at 40 with the end wall 6 of the box-like central portion and having also a depending outer flange 42 which is continuous from end to end of the frame. The webs 36, 36 likewise extend from end to end of the frame but are narrowed somewhat (Figure 3) adjacent the box-like central portion. Ribs 44, 44 are integrally formed with the flanges 42, 42 where they merge with the side walls 4, 4 of the central portion. Above the box-like central portion and merging therewith is formed the top annular flange 46 affording a means for

attaching a dust seal. The webs 36, 36 of each compression member are widened to merge with each other as at 48 adjacent the center box-portion and are beaded along their merging edges as at 50 (Figure 1). Where the webs 36, 36 merge with the annular flange 46 at the top of the frame, they overlie the corners of the central box-section as at 52, 52.

The pedestal jaw portion of each leg has a gusset-like member or rib 54 reinforcing its juncture with the upper portion of the tension member. On the outboard legs this takes a usual form, but on the inboard legs it is modified to afford a convenient manner of connection for tying means (not shown) extending between the frames at opposite sides of the truck. For this purpose, a bracket-like structure 56 is integrally formed between the pedestals 15 and the adjacent inclined portion of the tension member, said bracket comprising spaced ears 58 and 60 above and below the opening 62 afforded for said tying means which may be in the form of a tie rod with loops at each extremity. The ears 58 and 60 are afforded aligned openings 64, 64 for reception of a pin or other convenient securing means for the tie bar. In this modification, the tie means at opposite ends of the truck frame are located somewhat below the center line of the axles already indicated.

In the modification shown in Figures 4 to 13 inclusive, a structure generally similar to that just described is shown but differs therefrom in details more particularly set forth hereinafter. The side frame generally designated 102 has a box-like central portion substantially identical with that of the modification just described, said box-section forming a central well-like opening defined by end walls 104, 104 and side walls 106, 106 together with the cylindrical bottom wall 108, said end walls being continuous with the bottom wall 108 as in the previous modification and as best seen in the sectional view of Figure 5. The lateral or side walls 106, 106 extend below the bottom wall 108 as at 110, 110 (Figure 6) to merge with the bottom web 112 of the tension member of the frame. The bottom web 112 is cored away as at 111, 111 for convenient foundry practice. Vertical longitudinal reinforcing ribs 113, 113 extend between the bottom wall 108 and the web 112 and taper away outwardly of the end walls 104, 104 to merge with the web 112 as at 115, 115. The bottom web 112 is widened as at 114, 114 centrally of the frame and afforded reinforcing ribs 116, 116 (Figure 6) merging with the side walls 106, 106. Each end of the frame outwardly from the central portion is a bifurcated structure comprising two legs with each leg having a tension portion generally designated 118 and a compression portion generally designated 120, said tension and compression portions merging adjacent their ends as at 122 to afford spindle receiving means in the form of aligned openings 124, 124 at opposite ends of the frame. Around said aligned spindle openings 124, 124 are formed raised reinforcing and bearings pads 126, 126 of annular form. The tension and compression portions of each of the before-mentioned legs are of T-section, and the web 128 of the compression member extends around the end of the frame as at 130 and is continuous with the web 132 of the tension member. Likewise, the vertical leg 134 of the T-section of the compression member is continuous through the end portion 122 into the corresponding leg 136 of the T-section tension member.

Beading 138 (Figure 7) is formed around the edges of the openings 140, 140, said openings being defined at each end of the frame by the tension and compression members and the adjacent portion of the central box-section. The T-section tension and compression members are reinforced on their outer faces by the spaced ribs 142, 142. The middle portion of the compression member is reinforced by the outer flange 144 which tapers away adjacent the box-section to merge as at 146 (Figure 5) with the web of the compression member, and the U-section thus formed is reinforced by ribs 148, 148 extending between the flange 144 and the side wall 106, said ribs being cored away as at 149, 149. The web portions of the compression members at each end of the frame merge as at 150 (Figure 4) adjacent the central box-portion, and spaced upstanding lugs 152, 152 are formed thereon and afforded aligned openings 154, 154 for a securing pin, thus forming a means of support for brake hangers which may extend through openings 156, 156 in the web portion 150, said brake hangers supporting brake heads and brake shoes for cooperation with the wheels which are normally positioned between the opposite legs at each end of the frame.

Above the central box-section is formed the annular flange 158 beaded around its outer edge as at 164, said flange affording a means for attaching a dust seal. The said annular flange overlies as at 160, 160 (Figure 9) the corner portions of the aforementioned central well, said well affording a cavity for spring means and said spring means being afforded a rocking seat as at 162 on the cylindrical surface defined by the wall 108 at the bottom of said well. A wear plate (not shown) may afford a convenient bearing between a spring seat (not shown) forming a part of the spring assembly.

The inboard leg of the bifurcated portion at each end of the frame is afforded spaced lugs 166, 166 formed on the tension and compression members and afforded aligned openings 168, 168, said spaced lugs defining a jaw-like structure 45 for reception of securing means, such as a pin, for tie bars (not shown) extending between said inboard legs at each end of the frame. Said tie bar lugs 166, 166 are equally spaced above and below the axle center lines 170, 170, and the tie bars are thus positioned in the plane defined by the axle centers thus affording maximum stability for the side frames with respect to each other.

The modification shown in Figures 14 to 18 inclusive is somewhat similar to those already described being of truss form, and comprises the central box-section defined by the transverse vertical end walls 172, 172 and the longitudinal vertical lateral walls 174, 174 forming with the arcuate or cylindrical bottom wall 176 the center well or cavity 178 within which may be received a spring group (not shown). The side walls 174, 174 extend below the arcuate wall 176 as at 180, 180 (Figure 16) to join the bottom web 182 of the frame. Spaced reinforcing longitudinal ribs 184, 184 afford additional support between the arcuate wall 176 and the bottom web 182. The bottom web 182 is widened and formed with upstanding flanges 186, 186 (Figure 16) at opposite 70 sides of the frame, said flanges defining with the lateral walls 174, 174 U-sections with spaced reinforcing ribs 188, 188. Atop the central box-section is formed the annular flange 190 affording means of attaching a dust seal around that 75

portion of the bolster which is normally seated on the spring group positioned in the well 178 as aforesaid.

The opposite end portions of the frame are of 5 bifurcated form each comprising spaced inboard and outboard legs, and each of said legs having a top or compression member 192 and a bottom or tension member 194 merging adjacent their ends in a pedestal jaw structure 196 for reception 10 of wheel connecting means, such as a journal box (not shown). At the extremities of the jaws are formed aligned openings 198, 198 within which may be received securing means, such as a bolt, to retain said wheel connecting means in normal 15 position. The compression member 192 is of T-section comprising the vertical central web 200 which is continuous from end to end of the frame and merges centrally thereof with the vertical wall 174 already referred to, also said compression member comprises a top web 202 which likewise is continuous from end to end of the frame, and centrally of the frame is afforded a downturned longitudinal flange 204 (Figure 16) which tapers away at its opposite ends as best 20 seen in the side elevation of Figure 15. The top web 202 extends entirely around the jaw portion 196 to merge at the extremity of the jaw as at 206 with the extremity of the bottom web 208 of the tension member 194, said tension member 25 also being of T-section and comprising the vertical web 210, said vertical web 210 merging as at 212 (Figure 15) with the vertical web 200 of the compression member 192. The vertical web 210 is continuous from end to end of the frame and merges centrally thereof with the bottom portions of the side wall 174. The top webs 202, 202 of the respective legs at each end of the frame merge as at 212 adjacent the central box portion of the frame, and on the web 30 212 are formed the spaced upstanding lugs 214, 214, said lugs having aligned openings for mounting a pin or other securing means for the brake hanger which may be supported in the spaced openings 216, 216 in the said web 212.

For convenient foundry practice, cored openings are afforded as at 218, 218 in the bottom web 182 below the central well, and likewise openings are cored as at 220, 220 (Figure 15) in the vertical walls 174 below the arcuate wall 176.

On the outboard face of the central box-section is formed the horizontal longitudinal flange 222 (Figure 16) reinforced by the spaced vertical ribs 224, 224, said longitudinal flange forming support means for a brake rod (not shown). Above the longitudinal flange 222, the web 202 is extended outboard the frame to form the horizontal longitudinal flange 226 (Figure 16) which is slotted as at 228 to afford a connection for a pull rod or a chain for convenient movement of the truck when a locomotive is not available and without connection to the supported car body.

At the juncture of the tension and compression portions of the inboard leg at each end of the frame is formed a jaw 230 defined by spaced inturned lugs 232, 232 (Figure 17) with aligned openings 234, 234 for connection of a tie rod extending to the frame at the opposite side of the truck. Said jaws are diagonally arranged to conform to the configuration of the frame at the juncture of the tension and compression members, thus avoiding cutting into the contours of said members.

On the inboard leg of each tension member and adjacent the central box-section of the frame is formed a horizontal seat 236 (Figures 15 and

18) affording sliding means of support for a horizontal brake lever (not shown).

It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

I claim:

1. In a cast steel truss side frame, a central box-section having lateral and end walls and an arcuate wall continuous with said end walls defining a well open at the top, a bottom wall spaced from said arcuate wall, said lateral walls continuing below said arcuate wall to form with said bottom wall a box-section beneath said well, bifurcated end portions integral with said box-section and each comprising spaced legs formed with tension and compression members defining with said box-section aligned window openings and merging adjacent their ends to form spaced journal portions with aligned wheel hub openings, each of said tension and compression members having a T-section with an outer web and an inwardly directed flange, said outer webs merging and being continuous around said journal portions and through said box-section, thus forming a continuous web entirely around said frame.

2. In a truss side frame, a rectangular central portion having vertical lateral and end walls and an arcuate wall continuous with said end walls defining a well open at the top, a spaced bottom wall forming with said lateral walls and said arcuate wall a box-section beneath said well, integral bifurcated end portions each comprising spaced legs with tension and compression members having webs merging adjacent said central portion and extending entirely across said frame, the webs on said compression members comprising spaced brake securing means adjacent their juncture at each end of said frame, said means comprising spaced slots through said webs for the reception of the ends of associated brake hangers, and upstanding lugs atop said webs and adjacent said slots, said lugs affording means for the securing of said hangers.

3. In a cast steel truss side frame, a rectangular central portion having lateral and end walls and an arcuate wall continuous with said end walls defining a well open at the top, a spaced bottom wall forming with said lateral walls and said arcuate wall a box-section beneath said well, and integral bifurcated end portions, each comprising spaced legs with tension and compression members having webs merging adjacent said central portion and extending entirely across said frame, said compression and tension members having T-sections merging at opposite ends of

said frame with the transverse web of said T-section extending around said ends.

4. In a cast steel truss side frame, a rectangular central portion having lateral and end walls and an arcuate wall continuous with said end walls defining a well open at the top, a spaced bottom wall forming with said lateral walls and said arcuate wall a box-section beneath said well, and integral bifurcated end portions, each comprising spaced legs with tension and compression members having webs merging adjacent said central portion and extending entirely across said frame, each of said tension members being of T-section extending from end to end of said frame and continuous through said central portion, one of said members having a U-section at said central portion.

5. In a cast steel truss side frame, a central portion having lateral and end walls and an arcuate wall continuous with said end walls defining a well open at the top, a spaced bottom wall forming with said lateral walls and said arcuate wall a box-section beneath said well, and integral bifurcated end portions each including tension and compression members of T-section integral with said lateral walls and having webs merging adjacent said central portion and extending entirely across said frame, one of said members having a U-section along said central portion.

6. In a cast steel truss side frame, a central portion having lateral and end walls and an arcuate wall continuous with said end walls defining a well open at the top, a spaced bottom wall forming with said lateral walls and said arcuate wall a box-section beneath said well, and integral bifurcated end portions each including tension and compression members of T-section integral with said central portion with the transverse web of said T-section extending therearound, one of said members having a U-section along said central portion.

7. A truss type side frame comprising a central box portion and end portions of bifurcated form with inboard and outboard legs, said legs having tension and compression members merging in pedestal openings aligned transversely of the truck, and a brake lever seat on one of said tension members.

8. A truss type side frame comprising a central box-section and integral end portions of bifurcated form with inboard and outboard legs, said legs having tension and compression members merging in pedestal openings aligned transversely of the truck, and diagonally arranged jaw means formed adjacent the junctures of the tension and compression members of one of said legs affording means of connection to an associated frame.

ROBERT B. COTTRELL.
